COMBINED BOTTLE AND BASE THEREFOR

Robert J. Donoghue, Windsor, Conn., assignor to Emhart Corporation, Bloomfield, Conn.

Filed July 24, 1970, Ser. No. 44,113

Term of patent 14 years

Int. Cl. D9—01

U.S. Cl. D9—12

FIG. 2

FIG. 5

FIG. 3

FIG. 1

FIG. 4

FIG. 1 is a perspective view of a combined bottle and base therefor showing my new design;

FIG. 2 is a top plan view on a reduced scale;

FIG. 3 is an elevational view on the same scale as FIG. 2;

FIG. 4 is a bottom plan view thereof; and

FIG. 5 is an enlarged, fragmentary sectional view taken on the line 5—5 of FIG. 2.

I claim:

The ornamental design for a combined bottle and base therefor, as shown.
